UNITED STATES PATENT OFFICE.

SAMUEL OLDEHAM, OF PHILADELPHIA, PENNSYLVANIA.

CLUTCH FOR A PNEUMATIC HAMMER.

1,141,206.

Specification of Letters Patent.

Patented June 1, 1915.

Application filed December 31, 1914. Serial No. 378,862.

To all whom it may concern:

Be it known that I, SAMUEL OLDEHAM, a citizen of the United States, residing in the city and county of Philadelphia, State of Pennsylvania, have invented a new and useful Clutch for Pneumatic Hammers, of which the following is a specification.

My invention consists of a clip device for retaining the working tool, such as a rivet-set or similar tool, in the end of the barrel of a pneumatic percussion tool, to retain such tool in the end of the barrel and prevent it and the plunger of the hammering tool from shooting off from the tool when motive fluid enters the barrel and the tool is not bearing against its work.

It also consists of such clip device which is adaptable to retain the working tool in a riveter or similar percussion tool and which may easily be removed and again secured to the hammer for the purpose of renewing or replacing the working tool or set.

It further consists of other novel features of construction, all as will be hereinafter fully set forth.

In pneumatic riveters and similar percussion tools, if no clips or other fasteners are employed, the rivet-set and plunger in the working cylinder are liable to drop out at the end of the tool-cylinder if the lower end of the same is pointed downward, which is liable to cause the loss of said parts, when used in bridge or structural work, and will cause useless waste of expensive elements and delay the work in hunting for the plunger and set and in replacing the parts. Serious damages can be caused by dropping the set and plunger from high structures, and if the plunger and tool is shot out of the barrel under a pressure of about one-hundred pounds or more, which usually is the air-pressure for working, said elements can have the effect of projectiles in a fire-arm within a considerable distance.

My improved fastening is adaptable to the majority of riveting hammers of the usual constructions and with the use of the ordinary construction of rivet-set and other tool, so that the device can be employed by the hammering tools in general use and usually found on the market.

The annexed drawings and the following

description set forth in detail one mechanical form embodying the invention, such detail construction being but one of various mechanical forms in which the principle of the invention may be used.

In said annexed drawings—Figure 1 represents a side elevation, partly in section, of a pneumatic riveting hammer, illustrating one form of embodying my invention to use in a percussion tool such as a riveter. Fig. 2 represents a side elevation, partly in section, of the tool and attachment at a right angle to that in Fig. 1. Fig. 3 represents a transverse section on the line $\alpha-\alpha$ in Figs. 1 and 2. Fig. 4 represents a detail view of the locking and adjusting device employed in the tool.

Similar numerals of reference indicate corresponding parts in the figures.

Referring to the drawings, the reference numeral 1 indicates the barrel or piston-cylinder in which the plunger (not illustrated) is reciprocable.

A socket, 2, having a handle, 3, is secured upon the upper end of the barrel and said handle has the usual socket, 4, for attaching the air-hose and the usual trigger, 5, for controlling the throttle-valve.

An open socket, 6, fits upon the lower end of the barrel and has a flange, 7, around the edge of the opening, and two slightly transversely curved bars, 8, extend from and are integral with the upper edge of the socket 6 and bear against the sides of the barrel. The upper ends of said bars are bent outward to form perforated ears, 9, and the bars have a loose fit on opposite sides of the barrel.

The screw-threaded ends, 10, of a bail, 11, which straddles the end of the handle-socket within the handle, are inserted through the perforated ears and have spiral springs, 12, upon said ends and bearing against the ears and against thumb-nuts, 13, upon the threaded ends.

The lower faces of the ears have lugs, 14, which engage notches, 15, in the upper faces of the upper ends of the coiled springs, and the upper faces of the bodies of the thumb-nuts have similar lugs, 16, engaging notches, 17, in the lower faces of the lower ends of the coiled springs.

The lower end of the barrel fits freely within the socket and the rivet-set, 18, has its shank, 19, fitting in the tool-socket, 20, of the barrel and an annular wide groove 5 or recess, 21, in the periphery of its head, 22.

A split locking-collet, 23, fits within the socket and has its body loosely fitted around the head of the rivet-set and an interior annular rib or flange, 24, engaging the annular recess in the periphery of the set. 10

In practice, the split collet is placed in the socket together with the rivet-set, so that said collet is confined in the socket and its interior rib engages the annular recess and 15 admits of the set having limited longitudinal play within the collet but being retained by the collet from passing out through the opening in the bottom of the socket. The barrel of the tool is now inserted between the 20 arms with its end bearing in the socket and against the upper edge of the split ring, and the bail is placed to straddle the handle socket and enter the ears of the bars, whereupon the coiled springs and the thumb-nuts 25 are placed upon the screw-threaded legs of the bail. When the tool is started and its piston imparts blows upon the shank of the set, such blows will drive the set down freely, as longitudinal play is provided by 30 the annular recess of the set upon the internal rib of the split collet, and the down-stroke of the set will be absorbed by the split-collet and socket cushioning on the spring-coils, thus modifying the recoil of 35 the stroke. The lugs on the thumb-nuts and ears and the notches in the ends of the coiled springs will prevent the springs and nuts from turning on the threaded legs of the bail.

40 This safety attachment for the rivet-set is adapted for use with the usual riveting tools and rivet-sets, without necessitating any changes in these elements, and accidents and loss from the sets and pistons being shot out 45 of the hammer are prevented.

If the rivet-set has only one peripheral rib, 25, at the upper end of its head instead of the peripheral recess, as is desirable in small sized sets, a solid locking-collet can be 50 used instead of a split collet, and the set is then dropped through the collet at the upper end of the same, when the set, collet and lower end of the barrel is inserted in the socket in the same manner as in the first- 55 described device, and will perform the same function as said device.

Other modes of applying the principle of my invention may be employed for the mode herein explained. Change may therefore be 60 made as regards the mechanism thus disclosed, provided the principles of construction set forth, respectively, in the following claims are employed.

Having thus described my invention, what I claim as new and desire to secure by Letters Patent, is:—

1. In a clutch for a pneumatic hammer, an open socket adapted to movably fit upon the lower end of the hammer-barrel and having an annular flange in its bottom opening, a bail adapted to straddle the end of the handle-socket, yielding connections between the legs of the bail and the socket, and a split collet adapted to slidably fit in the socket and adapted to engage a rivet-set to have 75 limited longitudinal play within it.

2. In a clutch for a pneumatic hammer, an open socket adapted to movably fit upon the lower end of a hammer-barrel and having bars adapted to bear against the sides of the latter and said open socket having an annular flange, a bail, adapted to straddle the handle-socket, expanding and contractible connections between the legs of the bail and the bars of the socket, and a split collet 85 adapted to slidably fit in the socket and to receive a rivet-set having limited longitudinal play in the same.

3. In a clutch for a pneumatic hammer, an open-ended socket adapted to movably fit 90 upon the lower end of a hammer-barrel and formed with means for supporting a rivet-set longitudinally movable therein and upwardly extending bars adapted to bear against the sides of the barrel and formed 95 with perforated ears at their upper ends, a bail adapted to straddle the handle-socket of the hammer and having screw-threaded legs projecting through said ears, nuts upon said screw-threaded legs, and coil-springs upon 100 said legs and bearing against said ears and nuts.

4. A pneumatic percussion tool and a rivet-set having a shank fitting in the barrel of the tool and having a wide peripheral recess, a socket having an open bottom formed with an annular flange and adapted to movably fit upon the lower end of the tool-barrel and provided with bars adapted to extend upward along the sides of the barrel and 110 formed with perforated ears at their upper ends, a bail straddling the handle socket and having screw-threaded legs projecting through said ears, nuts upon said threaded legs, coil-springs upon said legs between the 115 ears and nuts, and a split collet movable within the socket and formed with an interior flange movable in the recess of the rivet-set.

5. In a clutch for a pneumatic hammer, an 120 open socket adapted to movably fit upon the lower end of the hammer-barrel and having an annular flange in its bottom opening, a bail adapted to straddle the end of the handle-socket, yielding connections between the 125 legs of the bail and the socket, and a collet

adapted to slidably fit in the socket and adapted to engage a rivet-set to have limited longitudinal play within it.

6. In a clutch for a pneumatic hammer, an open socket adapted to slidably fit upon the lower end of a hammer-barrel, expansible and contractible means adapted to pass around the upper end of the barrel and secured to said socket, a rivet-set having an

annular peripheral rib upon its head, and 10 a collet having an interior flange engaging said rib and limitedly longitudinally movable in the socket.
